UNITED STATES PATENT OFFICE.

ROBERT JAMES KELLETT, OF SAN FRANCISCO, CALIFORNIA.

IMPROVEMENT IN PUNCHES FOR CAR-TICKETS, &c.

Specification forming part of Letters Patent No. **65,090**, dated May 28, 1867.

To all whom it may concern:

Be it known that I, ROBERT JAMES KELLETT, of San Francisco city and county, State of California, have invented an Improved Indicator for Car and Omnibus Tickets; and I do hereby declare the following description and accompanying drawings are sufficient to enable any person skilled in the art or science to which it most nearly appertains to make and use my said invention without further invention or experiment.

The nature of my invention is to provide an improved mode of ascertaining the number of passengers who ride in a public conveyance, the number of fares taken, and the number of tickets sold, or, in other words, a check on forgetful or dishonest conductors.

It is intended to use a series of tickets, (to be used with my invention,) combining a number of fares in one, and each side shall be indicated by a hole in the ticket until it becomes forfeit, and also that the conductor shall receive no money for fares unless he give a ticket for the money so taken, and shall reclaim the ticket again during the trip, or immediately perforate a hole in it with a punch, the cuttings of which are retained and fall into a box attached to the punch, and are counted to correspond with the number of fares during the day or trip. Different colors in the tickets may indicate the difference in price. For instance, a yellow ticket may indicate a single fare, and a red ticket a fare from tickets at the lowest rates, to be punched when collected, to be issued but once; and by counting the cuttings or chips in the box,

(which is locked and the key in possession of the clerk,) the clerk is enabled to settle with the conductor. To more fully illustrate my invention, reference is had to the accompanying drawings and to the letters marked thereon.

Figure 1 is a side view. Fig. 2 is a sectional view.

Similar letters indicate like parts in each of the figures.

A A are the handles; B B¹, the jaws. B² is a spring for separating the jaws. Near the end of the upper jaw, B, is placed the punch g. The punch (a pin of solid steel) is inclosed in a gutta-percha case, C, attached to the jaw (the upper one) and the spring D, which has a hole through it to allow the punch to come down upon the upper face of the lower jaw, passing through the hole h, thereby cutting out the chip, which falls into the box E. This box is hinged at l, and when closed is held by spring m and catch n, or any other manner, and may be opened by the key F.

Having thus described my invention, what I claim, and desire to secure by Letters Patent, is—

A punch with an attachment, E, or its equivalent, for holding the clippings or chips of tickets, in the manner substantially as and for the purpose specified.

In witness whereof I have hereunto set my hand and seal.

R. J. KELLETT. [L. S.]
